UNITED STATES PATENT OFFICE

2,492,818

APPARATUS HAVING RELATIVELY MOVABLE MEMBERS AND FASTENING MECHANISM THEREFOR

August A. Saul, Ross Township, Allegheny County, Pa., assignor to Miller Printing Machinery Co., Pittsburgh, Pa., a corporation of Pennsylvania

Original application April 3, 1941, Serial No. 386,651. Divided and this application August 17, 1945, Serial No. 610,974

6 Claims. (Cl. 271—63)

1

This invention relates to apparatus having relatively movable members and fastening mechanism therefor. It embodies a number of improvement features in apparatus having relatively movable members and fastening mechanism therefor which may be employed in connection with material handling apparatus but which are also of great utility in other mechanisms and in the field of machinery generally.

The invention will be illustrated as embodied in material handling apparatus and specifically in sheet delivery apparatus for printing presses. Sheet delivery apparatus is apparatus for handling sheets relatively to a printing press while the press is in operation. While the word "delivery" is sometimes used to relate particularly to the handling of the sheets from the press after they have been printed or otherwise acted upon therein, in the present application, unless the context otherwise requires, the word "delivery" is used in a broader sense and applies to the handling of sheets or other material to a printing press or other mechanism acting thereon as well as handling the same away from such press or other mechanism.

The particular mechanism shown in the drawings is a sheet delivery mechanism for delivering sheets which have been printed or otherwise acted upon in a printing or like press away from such press and piling the same. The delivery mechanism is itself bodily movable toward and from the press. Such movement is through suitable control and operating devices and is accompanied by operation of connections between the delivery and press. Means are provided for initiating and terminating relative movements between the delivery and press in predetermined manner. Means are provided for stopping relative movement of the delivery and press toward each other before they reach cooperative position, and fastening mechanism is provided for fastening the delivery and press together in cooperative position.

The fastening mechanism preferably comprises portions adapted to be carried respectively by the delivery and press or other relatively movable members, one of such portions being adapted to lie behind the other to draw said members together, and means for advancing the first mentioned portion and also moving the same transversely to position it behind the other portion and then retracting the first mentioned portion to draw the members together. Desirably the fastening mechanism comprises a fastening

member having an engaging portion, an eccentric mounting for the fastening member whereby it can be advanced and retracted, a fulcrum member and means for urging the fastening member against the fulcrum member while the fastening member is being advanced and retracted whereby the engaging portion of the fastening member partakes of transverse movement simultaneously with advance and retraction.

This application is a division of my copending application Serial No. 386,651, now Patent No. 2,400,890, dated May 28, 1946.

Other details, objects and advantages of the invention will become apparent as the following description of a present preferred embodiment thereof proceeds.

In the accompanying drawings I have shown a present preferred embodiment of the invention, in which

Figure 1 is a side elevational view of sheet delivery apparatus with a portion broken away;

Figure 2 is a vertical transverse cross-sectional view taken on the line II—II of Figure 1 but with parts omitted for clarity;

Figure 3 is a detail view of a portion of the structure of Figure 1 with parts omitted for the sake of clearness and showing certain parts in one operative position;

Figure 4 is a view similar to Figure 3 showing the parts in a different operative position;

Figure 5 is a fragmentary horizontal cross-sectional view taken on the line V—V of Figure 2; and

Figure 6 is a fragmentary vertical longitudinal cross-sectional view to enlarged scale taken on the line VI—VI of Figure 5.

Referring now more particularly to the drawings, a printing press is indicated diagrammatically at 2 but is not shown in detail since the present invention does not relate to the press structure per se. The press may print upon sheets passed therethrough or it may be equipped with cutting and creasing blades or other instrumentalities for acting on the sheets. Adapted to cooperate with the press and deliver sheets therefrom is a delivery mechanism designated generally by reference numeral 3. The delivery apparatus, which will be hereinafter referred to simply as a delivery, comprises opposed side frame members 4 and cross frame members 5 connected together to support and contain the delivery mechanism. The delivery is separate from the press and is adapted to be moved in a straight

line toward and away from the press into and out of cooperative relationship with respect thereto. This provides a working space between the press and delivery. The delivery and press are relatively movable and while in the structure shown the press is stationarily mounted and the delivery moves over the floor the reverse might by the case or the press and delivery might both move.

Extending away from the press and stationarily mounted upon the floor is a supporting and guiding track 6 upon which one side of the delivery is supported and guided through rollers 7. The delivery and track have interfitting portions 8 and 9, respectively, as shown in Figure 2, to insure proper positioning of the delivery at all times and prevent tilting thereof. At its opposite side the delivery carries a wheel 10 through which it is supported directly upon the floor. The delivery has bearings 11 and 12, respectively, wherein are rotatively journaled shafts 13 and 14, respectively. The shaft 13 is connected through a universal joint 15 with a screw 16 extending toward the press, and the shaft 14 is connected through a universal joint 17 with a screw 18 extending toward the press. Fixed to the shafts 13 and 14 are sprockets 19 and 20, respectively. Journaled in the delivery are stub shafts 21 and 22 carrying idler sprockets 23 and 24, respectively. Mounted in the delivery is an electric motor 25 whose shaft 26 carries a bevel pinion 27. The bevel pinion 27 meshes with a bevel gear 28 fixed to a driving shaft 29 journaled for rotation in the delivery and to which is also fixed a driving sprocket 30. A sprocket chain 31 meshes with the sprockets 30, 23, 19, 20 and 24, as shown in Figure 2. The mountings for the idler sprockets 23 and 24 may be such that these sprockets or one thereof may be shifted to suitably adjust the tension of the sprocket chain 31.

The press 2 comprises a base 32 having fixedly mounted therein nuts 33 and 34 with which the screws 16 and 18, respectively, are in threaded engagement. The screws 16 and 18 are of the same size, hand and pitch and the sprockets 19 and 20 are of the same size, so when the motor 25 is operated both of the screws 16 and 18 will turn in the same direction at the same speed and will cooperate in exactly similar manner with the respective nuts 33 and 34 through which they pass. Since the nuts 33 and 34 are fixedly positioned in the press base, driving of the screws by the motor 25 will inevitably result in movement of the delivery toward or from the press depending upon the direction in which the motor armature turns. Preferably the motor is a reversing motor so that it may be driven in either direction. Consequently when it is desired to move the delivery toward the press the motor is driven in one direction and when it is desired to move the delivery away from the press the motor is driven in the opposite direction.

Pivoted to the body of the delivery 3 by a cross shaft 35 is a frame 36 carrying one end of each of a plurality of endless conveyors. The frame 36 is adapted to be swung about the pivot 35 from its generally horizontal operative position, as shown in Figures 1 and 3, to its raised inoperative position as shown in Figure 4. Means are provided for raising the frame 36 automatically upon movement of the delivery away from the press and for lowering the frame into operative position upon movement of the delivery toward the press.

Mounted in the delivery frame is a shaft 89 having fixed thereto a manually operable con-

trol handle 90 which is positioned outside the frame. Also fixed to the shaft 89 inside the frame is a pinion 91. Mounted in the delivery frame is a shaft 92 to which is fixed a gear segment 93 meshing with the pinion 91. Thus turning of the handle 90 causes through the pinion 91 and the segment 93 turning of the shaft 92 through a limited angle.

Fixed to the shaft 92 is an eccentric 107. Surrounding the eccentric 107 is an eccentric strap 108 forming one end of an arm 109 having an upwardly facing hook 110 at its opposite end. Mounted in the delivery frame is a stationary fulcrum pin 111. The arm 109 has a lateral projection 112 which underlies the fulcrum pin 111. The arm 109 is normally urged upwardly by a coil spring 113 connected to the arm at 114 and to the delivery frame at 115. The press has a latch plate 116 with which the hook 110 is adapted to cooperate to mechanically latch the delivery to the press during operation.

As the parts are shown in Figure 1 the center of the eccentric 107 is generally to the left of the center of the shaft 92. When the delivery 25 is to be moved away from the press the handle 90 is turned through two revolutions in the counter-clockwise direction viewing Figure 1 and this turning of the handle is accompanied by rotation of the shaft 92 to a limited extent in the clockwise direction. Such clockwise turning of the shaft 92 swings the eccentric upwardly and toward the right viewing Figure 1. But since the fulcrum pin 111 is stationary such swinging of the eccentric causes the arm 109 to pivot about the fulcrum pin 111 and the hook or latch 110 moves downwardly and disengages from the latch plate 116 on the press. This severs the mechanical connection between the delivery and press and frees the delivery for movement away from the press.

When the delivery is away from the press and ready to be moved back toward the press the handle 90, eccentric 107 and arm 109 are moved to the position shown in Figure 1. As the delivery approaches the press the inclined forward surface 117 of the hook 110 rides down on the latch plate 116. For reasons presently to be explained the delivery ordinarily stops a fraction of an inch away from the press so that it does not move quite far enough for the arm 109 to swing back up under the action of the spring 113 to engage the latch 110 over the latch plate 116 as shown in Figure 1. When the parts are thus positioned the handle 90 is turned in the counter-clockwise direction somewhat less than two complete revolutions. This, as above explained, is accompanied by turning of the shaft 92 and movement of the center of the eccentric 107 generally upwardly and toward the right viewing Figure 1. But the lateral component of such movement moves the arm 109 as a whole to the right sufficiently for the latch 110 to clear the plate 116 and when this has occurred the spring 113 pulls up the latch into latching engagement 50 with the plate 116. The handle 90 is then turned back in the clockwise direction to the position shown in Figure 1, which swings the eccentric 107 downwardly and toward the left. This tends to move the arm 109 to the left, but since the opposite end of the arm is firmly hooked or latched to the press the result is that during such clockwise turning of the handle 90 the delivery is by the arm 109 through the eccentric 107 drawn up firmly and tightly against the press.

While only a single arm 109 and associated

mechanism have been described above I prefer to employ two such arms, one adjacent each side of the delivery, the two arms being identical and operating synchronously. This causes the delivery and press to be drawn together firmly adjacent both side frames.

It has been explained above that operation of the motor 25 in one direction or the other causes rotation of the screws 16 and 18 to move the delivery toward or from the press. The motor circuit is controlled by four switches, one for closing the circuit to start the motor in one direction to move the delivery out, a second for opening such circuit to stop outward movement of the delivery, a third for closing the circuit to start the motor in the reverse direction to move the delivery in, and a fourth for opening such circuit to stop inward movement of the delivery. The delivery being in the out position, the handle 90 is turned in the clockwise direction to the position of Figure 1. Fixed to the shaft 92 is a pair of switch operating arms 118 and 119. When the handle 90 is moved as above described the arm 118 operates a switch 120 which closes the motor circuit to operate the motor in the direction to cause the delivery to move inwardly toward the press. The switch 120 is mounted on the frame of the delivery adjacent the shaft 92 and in position to be operated by the arm 118 upon movement of the handle 90 as just explained. The delivery continues its inward movement until a switch operating member 121 on the press operates a switch 122 on the delivery which opens said motor circuit and stops inward movement of the delivery toward the press. The switch 122 and switch operating member 121 are so positioned that the switch 122 is operated to stop the delivery a fraction of an inch before it reaches its fully operative position adjacent the press as above explained. Thereafter manipulation of the handle 90 as above explained draws the delivery up tight against the press.

When the delivery is to be moved out away from the press the handle 90 is turned to the position shown in Figure 4. This is done by turning the handle in the counter-clockwise direction from the position of Figures 1 and 3 through two revolutions. This causes the switch operating arm 119 (see Figure 6) to swing upwardly and operate a switch 123 carried by the delivery adjacent the shaft 92 to close the circuit which operates the motor in the direction opposite that in which the delivery is moved in toward the press. Consequently the delivery moves outwardly away from the press. This movement is accompanied by downward movement of a link 67. Such link carries a switch operating arm 124, which when the delivery has reached its full outward position operates a switch 125 carried by the delivery adjacent the link 67. Operation of the switch 125 opens the circuit and the delivery stops.

The handle 90 controls the motor for moving the delivery and the mechanical connection or latch for holding the delivery in place against the press. When the delivery is in, as shown in Figure 1, turning of the handle 90 through two revolutions in the counter-clockwise direction releases the latch 110 and initiates operation of the motor to move the delivery out. The handle 90 also initiates operation of the motor to move the delivery in and positions the arm 109 to adapt it to cooperate with the press when the delivery moves in. The delivery automatically stops a fraction of an inch short of its ultimate posi-

tion and again the same handle 90 simply by being turned somewhat less than two revolutions first in the counter-clockwise direction from the position shown in Figure 1 and then back in the clockwise direction to that same position causes the hook 110 to draw the delivery firmly up against the press. Thus a minimum of manual effort is needed to move the delivery toward and from the press.

The handle 90 has a grip portion 192 having an inwardly projecting pin 193 urged inwardly by a spring (not shown). The side frame carries a hollow outward projection 194 into which the pin 193 is adapted to project when the handle is stationary to hold it in position. To operate the handle the grip portion 192 is grasped and pulled outwardly and the handle turned and after completion of the turning operation the pin 193 is positioned opposite the hollow outward projection 194 and the grip portion 192 released to hold the handle in place.

While I have shown and described a present preferred embodiment of the invention it is to be distinctly understood that the same is not limited thereto but may be otherwise variously embodied within the scope of the following claims.

I claim:

1. Fastening mechanism comprising a fastening member having an engaging portion, an eccentric mounting for said fastening member whereby it can be extended and retracted, yieldable means urging said fastening member to turn about said eccentric mounting and means cooperating with said fastening member causing the same to tilt upon turning of said eccentric mounting.

2. Fastening mechanism comprising a fastening member having an engaging portion, an eccentric mounting for said fastening member whereby it can be advanced and retracted, a fulcrum member and means for urging the fastening member against the fulcrum member while the fastening member is being advanced and retracted whereby the engaging portion of the fastening member partakes of transverse movement simultaneously with advance and retraction.

3. Fastening mechanism comprising an elongated fastening member, an eccentric mounting for said fastening member whereby it can be advanced and retracted, a fulcrum member and a spring for urging the fastening member against the fulcrum member while the fastening member is being advanced and retracted whereby the fastening member simultaneously slides against the fulcrum member and partakes of angular movement thereabout.

4. In combination, a pair of relatively movable members, means for moving said members relatively toward cooperative position adjacent each other, means for stopping said relative movement, said last mentioned means having a control portion positioned in the path of movement of a portion of at least one of said members to be engaged thereby upon movement of said member toward said cooperative position and located along said path at a point such that when it is so engaged said relative movement is stopped with said members slightly farther apart than when in said cooperative position, fastening means connected with one of said members and means for extending said fastening means to engage the other member and then retracting said fastening means to draw said members into said cooperative position.

5. In combination, a pair of relatively movable

members, means for moving said members relatively toward cooperative position adjacent each other, means for stopping said relative movement, said last mentioned means having a control portion positioned in the path of movement of a portion of at least one of said members to be engaged thereby upon movement of said member toward said cooperative position and located along said path at a point such that when it is so engaged said relative movement is stopped with said members slightly farther apart than when in said cooperative position, a control device having a portion sequentially movable to two positions, means operable by the control device in one of said positions to initiate operation of said first mentioned means and means operable by the control device in the other of said positions after said relative movement is stopped to further relatively move said members into said cooperative position.

6. In combination, a pair of relatively movable members, means for moving said members relatively toward cooperative position adjacent each other, means for stopping said relative movement, said last mentioned means having a control portion positioned in the path of movement of a portion of at least one of said members to be engaged thereby upon movement of said member toward said cooperative position and located along said path at a point such that when it is so engaged said relative movement is stopped with said members slightly farther apart than when in said cooperative position, fastening means con-

nected with one of said members, said fastening means having a portion adapted to lie behind a portion of the other member to draw said members together, and means moving said portion of the fastening means non-parallel to the direction of said relative movement to position it behind said portion of the second mentioned member and retracting said portion of the fastening means to draw said members into said cooperative position.
